UNITED STATES PATENT OFFICE.

HIRAM H. SPONENBURG, OF WADSWORTH, ILLINOIS, ASSIGNOR, BY DIRECT AND MESNE ASSIGNMENTS, TO LAAS & SPONENBURG CO., A CORPORATION OF ILLINOIS.

RAILROAD-RAIL STAY.

No. 872,693.

Specification of Letters Patent.

Patented Dec. 3, 1907.

Application filed February 14, 1907. Serial No. 357,395.

To all whom it may concern:

Be it known that I, HIRAM H. SPONENBURG, a citizen of the United States, residing at Wadsworth, in the county of Lake and State of Illinois, have invented certain new and useful Improvements in Railroad-Rail Stays, of which the following is a specification.

My invention relates to railroad rail-stays adapted to prevent the longitudinal creeping of the rail and has for its object to provide a durable stay which shall have a locked grip, or engagement, with the rail flange and in which the parts are simple, inexpensive and easily assembled.

15 The device of my invention, in its essentials, consists of a bar adapted to extend underneath the rail flange and to abut a tie, the bar being provided with rigid jaws, between one of which, and the rail, is interposed a 20 gripping plate held in suitable locked engagement with the rail flange and the body of the stay.

The invention has for its object more particularly to provide a bifurcated key which 25 is split over a rigid projection to hold the gripping-plate in position.

In constructions somewhat similar to that above outlined, some inconvenience has resulted, in practice, from mislaying such loose 30 parts as the gripping-plate. To prevent this, my invention contemplates holding the gripping-plate within the jaw on the stay, but in such a manner that it may move freely. It has also been found by experience 35 that a key projecting across the tie is likely to become loosened by vibration of the track on the road-bed.

My invention has for a further object to so 40 construct the stay in this respect that the inner end of the wedge stands above the tie. Preferably the stay is made with a bend or constructed on lines which are oblique with respect to the cross-tie, so that the grip of the rail tends to bind the rail in its engagement 45 with the stay. This construction has a disadvantage, however, and particularly when the body of the stay is made of tough, though soft, malleable iron, in that the flange of the rail is likely to cut into the corner of the stay. 50 To remedy this, I provide the stay at this place with an inset of hard metal. It will be understood that these various improvements may be all embodied in one stay, or such of them may be utilized as may be deemed 55 necessary to meet the particular conditions.

The invention has for a further object to provide the improvements in structure and arrangement of parts which are shown in the drawings and which will be described in the following specification. 60

I have illustrated a convenient embodiment of my invention, together with certain suggestive and typical modifications in the accompanying drawings, wherein—

Figure 1 is a side elevation of a stay shown 65 in position upon the rail flange. Fig. 2 is a perspective view of the gripping or clamping block. Fig. 3 is a sectional plan on the line A—B of Fig. 1. Fig. 4 is an inverted plan view of the stay. Fig. 5 is a vertical section 70 on the line C—D of Fig. 1. Fig. 6 is a like view on the line E—F of Fig. 1. Fig. 7 is a detail, in perspective, of the end of one of the jaws. Fig. 8 is a sectional plan of one end of the stay. Fig. 9 is a front elevation of the 75 gripping block. Fig. 10 is a vertical section on the line G—H of Fig. 9. Fig. 11 is a view similar to Fig. 8, showing a modified construction. Fig. 12 is a detailed elevation, illustrating the same modification. Fig. 13 is 80 a view similar to Fig. 11, showing the inner jaw face beveled. Fig. 14 is a sectional plan similar to Fig. 8, illustrating a modification. Fig. 15 is a vertical section showing the same 85 modification. Fig. 16 is a side elevation, illustrating the same modification. Fig. 17 is a side elevation of one end of the stay, showing the hardened inset-piece. Fig. 18 is a vertical section on the line I—J of Fig. 17. Fig. 19 is a section through the jaw at this 90 end of the stay. Fig. 20 is a perspective view of the inset-piece. Fig. 21 is a side elevation, partly in section, illustrating a modified form of stay in which the key is vertical. Fig. 22 is a sectional plan on the line K—L of 95 Fig. 21. Fig. 23 is a vertical section on the line M—N of Fig. 21; and Fig. 24 is a detailed plan of the jaw with the key removed.

Like numerals of reference indicate the same parts in the several figures of the drawings. 100

Referring particularly to Figs. 1 to 10, inclusive, 1 represents the rail having the flange 2, under which extends the bar 3, or body of the stay, having the abutment 4 which lies against the cross-tie 5. The bar is provided with a preferably integral hook or jaw 6 at one end, and a somewhat wider, larger jaw, or hook, 7 at the other end. The bar, it will be seen from Figs. 3. and 4, is 110

formed with a bend so that the end having the jaw 6 stands away from the tie. The bar is preferably made with the strengthening ribs 8, 9, 10, the central ribs 9 being carried over to the tie side of the stay at the end having the jaw 6. This arrangement provides for strengthening the stay at the place where the greatest strain comes, due to the oblique position of the stay with respect to the rail flange. The grip of the rail will tend to carry the jaw 6 toward the tie. Preferably the rail flange engages immediately with the jaw 6. At the other side of the rail I provide movable gripping means interposed between the body of the stay and the flange, together with devices for locking said gripping means in position. Such means may consist of a block or plate 11 which is adapted to be freely movable within the jaw 7. The block is preferably provided with ribs 12, 12, extending into guide channels 13, 13, in the stay, and on its upper face with ribs 14, 14, which slide in channels 15, 15, on the inside of the jaw. The upper face of the block has a channel 16, into which extends a lug 17 on the end of the jaw. This lug will be cast horizontal and may be hammered down into the groove when the block has been put in place. It will be seen, therefore, that the block may slide back and forth in the jaw and at the same time cannot be displaced. The block is preferably of hard cast iron and is formed with an oblique face 18 to engage the top of the rail flange, and a vertical face 19 provided with ribs 20, preferably set obliquely and which are designed to bite into the edge of the rail flange. The block is clamped on the rail flange by means of a key 21 which is driven in between the jaw and the back of the block. I prefer to provide locking means for preventing the vibration of the road-bed, or other cause, from displacing the key. This locking of the key may be accomplished by bifurcating it and driving it over a rigid projection on the stay. Preferably the key is bifurcated by a slot near one edge so as to provide a relatively thin, flexible leaf 22 which, by being bent and cramped against the tie, prevents the key from slipping back. In Figs. 5 and 8, I have shown the projection over which the key is split as a horizontally disposed, wedge-like, integral lug 23 on the side of the stay. In Figs. 11 and 12, I have shown a modified arrangement, in which the key 24 has a vertical bifurcation and is driven over a vertically placed, wedge-like projection 25. Fig. 13 illustrates a modification in which the inner face of the jaw is beveled at 30, to increase the locking effect of the bending of the leaf 26. In Figs. 14 to 16, inclusive, I have shown a modified construction designed to give the key an oblique position so that its inner end stands above the tie. In this construction

the inside of the jaw 7 is provided with oblique faces 27, 27. It will be understood that this modification is perfectly adaptable to the construction shown in the preceding figure. It has been shown in separate drawings merely for the sake of clearness of illustration.

Figs. 17 to 20, inclusive, show the inset-piece for the jaw 6. This piece, designated by the numeral 28, is made of hard metal and preferably beveled, as shown in Fig. 21. It is set into an aperture in the jaw 6 and may be held in position by means of a lug 29 which can be cast so as to project from the side of the jaw and then be hammered over onto the inset-piece when the same has been inserted.

In Figs. 21 to 24, inclusive, I have shown a modified form of stay, in which the key has a vertical position. The jaw 31 has a perforation 32, and on the under side the wedge 33, the key 34 being split and driven over the wedge.

I wish it to be understood that I do not desire to be limited to the precise devices and arrangements herein shown and described, as obvious modifications will occur to persons skilled in the art.

I claim:

1. In a rail-stay, the combination of a bar, with rail-clamping means associated with the bar at each end, a split key to hold said means in engagement with the rail flange, and a fixed projection to force the leaves of the split key apart.

2. In a rail-stay, the combination of a bar, with rail-clamping means associated with the bar at each end, a key to hold said means in engagement with the rail flange, said key having a bifurcation forming a relatively thin leaf, and a projection to force the leaf outwardly.

3. In a rail-stay, the combination of a bar, with rail-clamping jaws at each end of the bar, a split key in one of the jaws, and a projection to force the leaves of the split key apart.

4. In a rail-stay, the combination of a bar, with rail-clamping jaws at each end of the bar, a gripping plate associated with one of the jaws, a split key to hold the gripping plate against the flange of the rail and a projection to force the leaves of the split key apart.

5. In a rail-stay, the combination of a bar, with a rail-clamping jaw at one end of the bar, means for engaging the rail flange at the other end of the bar, a split key in the jaw, and a projection to force the leaves of the key apart, the inner surface of said jaw being beveled.

6. In a rail-stay, the combination of a bar, with clamping means at each end of the bar, a key to hold said clamping means in engagement with the rail flange, and a slanted key-way for the key to hold the inner end of the same out of contact with the cross-tie.

7. In a rail-stay, the combination of a bar having rail clamping jaws at each end, a slideable gripping plate in one of the jaws, a key to hold the gripping plate in contact with the rail flange, and an oblique key-way formed in said jaw to hold the end of the key out of contact with the cross-tie.
8. In a rail-stay, the combination of a bar having a rail-clamping jaw at each end, with a slideable block in one of the jaws, a split key to engage the block, a projection to force the leaves of the split key apart and an oblique key-way in said jaw to hold the end of the key above the cross-tie.
12. In a rail-stay, the combination of a bar, with means for engaging the rail at opposite sides so that said stay lies diagonally of the rail, said means comprising a jaw at 40 one end of the bar, and an inset-piece of hard metal on the inner face of the jaw having a substantially vertical exposed surface against which the rail flange lies.
13. In a rail-stay, the combination of a 45 bent bar one end of which abuts while the other is free from the tie, with a jaw free from the tie, and an inset-piece of hard metal at the corner of the jaw having a substantially vertical exposed surface against which the 50 rail flange lies.
14. In a rail-stay, the combination of a bar, with means for engaging the rail at opposite sides so that said stay lies diagonally of the rail, said means comprising a jaw, an 55 inset-piece at the corner of the jaw having a substantially vertical exposed surface against which the rail flange lies and a lug on the jaw to hold the same in position.
15. A rail stay, comprising engaging means 60 to engage the rail at opposite sides, in combination with a split key to be inserted in said rail stay to cause the engagement thereof with the rail, and a projection on the stay over which the key is split so as to force one 65 member thereof away from the other.
- 30 11. In a rail-stay, the combination of a bar, with rail engaging means at one end of the bar, a jaw at the other end of the bar, a gripping block in the jaw, oblique ribs on the face of the block engaging the rail flange and means for clamping the block against the rail flange.
